Specification for Design.

Patented Jan. 28, 1919.

Application filed December 22, 1916. Serial No. 138,506. Term of patent 14 years.

To all whom it may concern:

Be it known that I, WILLIAM F. MUEHLSTEIN, a citizen of the United States, residing at Atascadero, in the county of San Luis Obispo and State of California, have invented a new, original, and ornamental Design for Gas-Saving Plates, of which the following is a specification, reference being had to the accompanying drawing, forming a part thereof.

Figure 1 is a top plan view of a gas saving plate, showing my new design; and Fig. 2 is an edge view.

I claim:

The ornamental design for a gas saving plate, as shown.

WILLIAM F. MUEHLSTEIN.
